UNITED STATES PATENT OFFICE

HARRY S. CLARKE, OF LONG BEACH, CALIFORNIA

DESIGN FOR AN ARM FOR STREET-LIGHTING STANDARDS

Application filed March 9, 1929. Serial No. 30,415. Term of patent 3½ years.

To all whom it may concern:

Be it known that I, HARRY S. CLARKE, a citizen of the United States, residing at Long Beach, in the county of Los Angeles and State of California, have invented a new and original and ornamental Design for an Arm for Street-Lighting Standards, of which the following is a specification, reference being had to the accompanying drawing, forming a part thereof.

Figure 1 is a side elevation of the arm for street lighting standards, showing my design.

Figure 2 is a plan view of my design.

I claim:

The ornamental design for an arm for street lighting standards, as shown.

HARRY S. CLARKE.
